UNITED STATES PATENT OFFICE.

ARTHUR GRAHAM FRANCE, OF ADELPHI, LONDON, ENGLAND.

PRINTING APPARATUS.

Specification of Letters Patent. Patented Dec. 12, 1916.

1,208,125.

Application filed February 24, 1916. Serial No. 80,261.

To all whom it may concern:

Be it known that I, ARTHUR GRAHAM FRANCE, a subject of the King of Great Britain, residing at 1 Adam street, Adelphi, in the county of London, England, have invented certain new and useful Improvements in or Relating to Printing Apparatus, of which the following is a specification.

This invention relates to printing apparatus of the kind suitable for printing advertisements or other matter upon the tape used by shop-keepers for tying up packages and designed for automatic operation as the tape is withdrawn by hand for use from time to time from the immediate supply in or on the apparatus.

The main object of the said invention is to make provision whereby the printing type or the like may be readily changed or re-arranged by the shop-keeper or his assistants in order to vary the advertisements or other matter to be printed on the tape from time to time as desired but other objects of the said invention are to render the inking of the type or the like more uniform and reliable than in apparatus of the kind referred to as heretofore proposed, to provide means to obviate any danger of the tape not being properly fed into the printing apparatus and generally to produce a simple efficient and convenient apparatus not liable to get out of order and easy to manipulate.

According to the said invention, the type wheel or carrier is provided with resilient releasable clamping means for temporarily securing single letter type (that is, type, each body of which carries a single letter), whereby some of the type may be changed or rearranged without necessarily releasing the whole of the type, and means are provided whereby the type carrier may be readily removed from the apparatus for the purpose.

Other valuable features of the invention are that provision is made for the suspension of the apparatus above the place where the tape is to be used, with freedom for angular movement of the apparatus, and provision is made for proper supply of the tape to the type carrier, notwithstanding variations of the part where the tape leaves the supply reel, and a specially effective and simple inking roller is provided.

The said invention is hereinafter more particularly described with reference to the accompanying drawings which illustrate the

preferred embodiment of the said invention.

Figures 1 and 2 are elevations at right angles to one another of the complete apparatus in the position in which it is disposed for use; Fig. 3 is a face view of the printing mechanism contained in the lower part of the apparatus when the closure thereof is opened; Fig. 4 is a section taken on the line A—A Fig. 3; Fig. 5 is a horizontal section (drawn to a larger scale) of the inking roller; Fig. 6 is a face view of the same with its cover removed also drawn to a larger scale and Fig. 7 is a horizontal section of the impression roller drawn to a larger scale than Fig. 3.

In the following description the parts of the said figures are referred to by the letters marked thereon the same letters of reference indicating the same parts in the several figures of the drawings.

a is the containing case for the printing mechanism which case is drum shaped and provided with side arms *a'* *a''* by which it may be suspended from a shop ceiling or the like. The said arms *a'* *a''* are secured to the sides of the case and connected together at top by a screw bolt *a³*. The side *a⁴* of the case is hinged at bottom to the body of the case *a* so that when the said arms are disconnected access may be obtained to the interior of the case. The tape supply spool or reel *b* is mounted on a tubular axle *b'* passed through holes in the arms *a'* *a''* and secured in position by milled nuts *b²* *b²* screwed on its ends. One of these nuts must therefore be removed from the axle *b'* when it is desired to open the case *a*. The position of the hinged parts when being operated to open the case *a* is indicated in broken lines in Fig. 1. The arms *a'* *a''* are provided with dished guards *b⁸* *b⁹* on each side of the reel *b* such guards being respectively secured to the said arms around the apertures in them in which the tube *b'* is engaged.

The tape *c* passes from the reel *b* through a slot *a⁵* in the upper part of the case *a* to the printing mechanism and therefrom through a slot *a⁶* in the lower part of the said case to the user who draws it down through the apparatus when needed. In the course of supply of the tape *c* from the reel *b* from time to time the said tape leaves the said reel from a different lateral point thereon, and to avoid twisting or folding of the tape *c* in passing through the slot *a⁵* or non-engagement with the printing mechanism

which might occur if the point from which the tape leaves the reel b varied laterally from time to time relatively to the slot a^5 the said reel is narrower than the space between the guards b^3 b^4 and is so mounted on the tube b' that the reel may slide thereon laterally and adjust itself from time to time by reason of the tension on the tape, to a position in which the tape passes to the printing mechanism in a fairly direct manner.

The printing mechanism is arranged upon a frame d secured within the case a by screws d' d'' .

15 e is the type wheel rotatory upon the pin e' and secured thereon by a milled headed screw e^2 .

f is the rotatory impression roller mounted in a fork f' pivoted to the frame d a spring f^3 being arranged between the frame d and fork f' so as to cause the roller f to press the tape against the type wheel e .

20 g is a rotatory blotting roller over which the tape passes after leaving the type wheel and h is a rotatory inking roller carried by an arm h' pivoted to the frame d a spring h^2 being arranged in connection therewith to press the inking surface against the type face with even pressure.

25 30 i i' are guiding pins or rollers for the tape.

The type wheel e is made up of a disk e^3 with central bearing e^4 screwed at its outer end, a removable pressure disk e^5 , a metal washer e^6 and a rubber washer e^7 . The single letter type e^8 is arranged radially between the washer e^7 and the rear disk e^3 and is clamped in position by use of the screw fly nut e^9 engaging with the screwed

35 40 end of the bearing e^4 . The type is taper in the body and an annular projection e^{10} is provided on the face of the disk e^3 for the bottoms of the type to abut against whereby its arrangement in proper position is facilitated and insured.

45 By unscrewing the fly nut e^9 and thereby releasing the type changes in composition may be effected, the type wheel being first removed from the case a by removing the screw e^2 the rollers f h being pressed away from the type wheel

50 55 respectively, to admit of removal of the type wheel from the pin e' . The rubber washer e^7 is provided so that when only partial change in the type is desired the clamping pressure may be only partially released in order that, while some of the type may be easily withdrawn and replaced, the clamping pressure is still sufficient to retain the other type which it is not desired to move.

60 65 When the whole of the type is to be removed the fly nut e^9 , disk e^5 and washers e^6 e^7 are of course entirely removed from the part e^4 . Provision is thus made whereby by opening the case a as hereinbefore explained the type

wheel may be removed and new compositions of advertising matter made whenever the user of the apparatus so desires, and without the necessity for exercise of mechanical skill.

The impression roller f is flanged, the space between the flanges being the width of the tape. The impression surface is of rubber and is conveniently formed by springing an ordinary elastic rubber band f^3 into position between the flanges. An extremely simple and practically permanent elastic impression surface is thereby formed. The blotting roller g is flanged and around its body blotting paper is secured. The said roller may readily be removed for re-covering its surface with blotting paper by removing the screw g' .

The inking roller h is flanged and box-like. It consists of a cupped and flanged body h^3 and a disk h^4 which constitutes when in place one side and flange of the roller h . The said disk cover h^4 is kept in place by the removable screw nut h^5 which provision admits of access to the interior of the roller. The said nut h^5 screws upon the outer end of a tubular bearing or bush secured to or part of the body h^3 . Within the said interior the supply of ink is placed. In the cylindrical part of the body h^3 a slot h^6 and holes h^7 h^8 are provided. Through the slot h^6 one end of a length of cotton tape h^8 passes into the interior of the inking roller and the said tape is wound around the exterior thereof between its flanges several times to form the inking surface, the viscosity of the ink keeping the said tape h^8 in place. As the type takes up ink from the inking surface, ink is supplied thereto by passage from the interior of the inking roller along the tape h^8 , through the slot h^6 and perforations h^7 h^8 . When first arranging the tape h^8 in position it is smeared or soaked with ink.

The apparatus is supplied with tying up tape for use by opening the case, removing the reel b , winding tape upon it, replacing the reel, passing the free end of the tape through the slot a^6 over the guide pin i , between the type wheel e and impression roller f , partly around the blotting wheel g , over the guide pin i' and finally out through the slot a^8 in the bottom of the case a . The said case is then closed and the arms a' a'' secured together as hereinbefore described, and the apparatus suspended above the place where the tape is needed for use. When the free end of the tape is pulled down for use it rotates the type wheel and impression roller by frictional contact thereby receiving an impression from the face of the type which has been previously inked by the inking roller, which is rotated by the type wheel by frictional contact of the said type face on the inking surface. After being

printed on the printed face of the tape passes over the blotting paper surface of the blotting wheel (which is rotated by the frictional contact of the tape therewith) whereby smearing of the printed impression is avoided. The tape then passes to the operator below.

By the said invention a most effective advertising means is provided as change of 10 the advertised matter may very readily be effected.

What I claim and desire to secure by Letters Patent of the United States is:—

1. Tape printing apparatus of the kind hereinbefore referred to comprising in combination, a casing, a part of which is displaceable, a type carrier rotatable on a fixed pin within said casing, removable means on said pin for retaining said carrier in position thereon, means for supplying tape to said carrier, and type inking means.

2. Tape printing apparatus of the kind hereinbefore referred to comprising type inking means, a carrier for single letter type, type carried thereby, means for supplying tape to said type, and clamping means for securing said type in place comprising a screw nut, a bearing washer, and a flat piece of resilient compressible material for gripping the type.

3. Tape printing apparatus of the kind hereinbefore referred to comprising a tape supply reel free to adjust itself to the proper position for feeding the tape to the type carrier notwithstanding variation in position of the part when the tape leaves the supply.

Copies of this patent may be obtained for five cents each, by addressing the "Commissioner of Patents, Washington, D. C."

4. Tape printing apparatus of the kind hereinbefore referred to comprising a type carrier, type carried thereby, means for supplying tape to said type, means for inking the type, means for suspending the apparatus with freedom for angular movement within the place where the tape is to be supplied, and means for delivering the printed tape from the apparatus in a downward direction.

5. Tape printing apparatus of the kind hereinbefore referred to comprising in combination a carrier for single letter type and a tape supply reel free to adjust itself to the proper position for feeding the tape to the type carrier notwithstanding variation in position of the part where the tape leaves the supply.

6. Tape printing apparatus of the kind hereinbefore referred to comprising a type carrier, type inking means, and a tape supply reel free to adjust itself to the proper position for feeding the tape to the type carrier notwithstanding variation in the position of the point where the tape leaves the supply.

7. Tape printing apparatus of the kind hereinbefore referred to comprising a type carrier, single letter type carried thereby, said carrier including a disk, removable resilient and compressible means for forcing said type into contact with the disk, pivotally mounted means for forcing tape into contact with the type, and a pivotally mounted inking roller for said type.

ARTHUR GRAHAM FRANCE.
